JOSEPH MASSOLLE AND JOSEF ENGL. OF GRUNEWALD, AND HANS VOGT, OF BERLIN-SCHONEBERG, GERMANY, ASSIGNEES TO TRI-ERGON LIMITED, OF ZURICH, SWITZERLAND.

MEANS FOR RECORDING SOUND WAVES.

Application filed April 4, 1921. Serial No. 458,633.

To all whom it may concern:

Be it known that we, JOSEPH MASSOLLE, JOSEF ENGL, and HANS VOGT, citizens of the German Republic, residing, the first and second at Grunewald, the third at Berlin-Schoneberg, Germany, have invented certain new and useful Improvements in Means for Recording Sound Waves, of which the following is a specification.

10 In the recording of sound waves it is necessary, for example for optical acoustical operations (speaking film, gramophonic musical performances, acoustic advertisements, and the like) to fix the sound waves in order to be able to utilize the recorded symbols for reproduction.

This invention relates to an arrangement for recording sound waves in which the fixation on a moving film is effected photographically in such a manner that the sound waves act on a pencil of light rays in accordance with their frequency and intensity.

For this purpose the arrangement is so constructed that the energy of the sound is compressed and acts on a mirror mounted on one side. This mirror i. e., a diaphragm having a light-reflecting surface, has preferably a high individual frequency and is of small dimensions so that a maximum impressionability and great angle of rotation are obtained.

The invention may be practiced by the use of one reflecting diaphragm, or of several reflecting diaphragms, against which the sound waves will impinge and from the reflecting surfaces of which light rays will be reflected. These reflected rays will be utilized, for example, by recording the varying image photographically on a sensitized film, a record thereby being formed which corresponds to the variations of the original sound waves.

With diaphragms secured at one edge only, various advantages are secured. Thus, a minimum of power is required to obtain a desired movement of the diaphragm; a smaller diaphragm may be used to produce the same deflection, than with a diaphragm otherwise mounted, with the same exertion

of power upon it; and the light rays reflected from the reflecting diaphragm may be kept parallel, with each other, because the diaphragm remains plane upon deflection, in contradistinction to a diaphragm supported all the way around its periphery, which moves outwardly in a curve, so that rays impinging upon the same at an angle will not remain entirely parallel upon reflection therefrom.

When a plurality of reflecting diaphragms are used, they preferably have different individual natural rates of vibration, so chosen that they will reinforce sounds received by the diaphragms throughout a wide range. The construction also is preferably such that a damping effect is obtained at the diaphragms. Accordingly the recorded curve would have various resonance peaks, corresponding to the tones and overtones to which the various diaphragms respond, but for the fact that these peaks are somewhat flattened by the damping effect, whereby the resultant curve more correctly corresponds to the original sound vibrations.

The invention, in addition to its use for recording sound on sensitized surfaces, etc., may be utilized for other purposes, as for example, for causing the acoustically-controlled light to control the internal resistance of a light-sensitive cell.

The invention consists in arrangements and combinations in accordance with the foregoing, all as will be more fully described hereinafter and particularly pointed out in the appended claims.

In order that the invention may be more clearly understood, attention is hereby directed to the accompanying drawings, forming part of this application, and illustrating certain embodiments of the invention. In the drawings,

Fig. 1 is a diagrammatic sectional view illustrating the use of a single reflecting diaphragm;

Fig. 2 is a similar view, showing two reflecting diaphragms jointly covering the opening;

Fig. 3 is a diagrammatic, partial, enlarged

view of a film bearing a double sound record thereon, passing across a slit through which light reflected from the two diaphragms of Fig. 2 is projected;

5 Fig. 4 is a diagrammatic side elevation of the recording apparatus embodying a single reflecting diaphragm;

Fig. 5 is a similar view showing a modification;

10 Fig. 6 is a diagrammatic sectional view through a modified form of apparatus in which a plurality of reflecting diaphragms are used successively; and

15 Fig. 7 is a view similar to that of Fig. 4, but showing a light-sensitive cell in place of the sensitized film, to receive the acoustically-varied light.

The invention may be carried out for example by causing a collecting device O (sound horn see Fig. 4) which embraces great angular ranges to concentrate the energy of the sound on a reflecting diaphragm s^1 . This diaphragm is for example of rectangular form and is clamped fast on one side as shown by way of example in Fig. 1. It practically completely covers the orifice of the collecting device O. The dimensions of the diaphragm s^1 are preferably such that the highest possible individual frequency is ensured and that, owing to the small mass of the diaphragm a perceivable deflection is secured even with small sound energy. An individual frequency may be used (e. g. of 12000 to 15000) which lies beyond the frequencies usual in ordinary sound operations.

The invention may also be carried out so that, instead of the small mirror s^1 several, for example according to Fig. 2 two mirrors s^1 and s^2 are used which are mounted each at a point of its circumference opposite the point of the circumference at which the other mirror is fixed, so that they deflect, one, in the direction of a right hand rotation, the other, in the direction of a left hand rotation. Their dimensions are preferably so chosen that they possess different individual frequencies. It is of advantage to give the one diaphragm comparatively low individual vibration so that it acts specially on the individual vibrations of the vowels and their diphthongs. Its damping is suitably so chosen that the higher harmonics of its vibrations will not cause a disturbing effect. This is effected for example by the suitable choice of its distance from the attachment frame r (see Figs. 1 and 2). The second reflecting diaphragm is made of such dimensions, that it reproduces the high frequency vibrations of the consonants and sibilant sounds.

In order to record the movement of one of the reflecting diaphragms or of both diaphragms, a pencil of light from a source of light l (Fig. 4), is allowed to pass, through a system of lenses (not shown), on to the

reflecting surface of the diaphragm or mirror s^1 , Fig. 1, or the two diaphragms s^1 and s^2 , Fig. 2, and be reflected thereby, the reflected light being directed, for example, by a number of prisms p , to produce an image 70 of the light source on a slit sp . The inner edges of the two mirrors of Fig. 2 determine on the slit two limits g^1 , g^2 , (Fig. 3), between illuminated and unilluminated parts 75 of the slit. Their distance apart can be fixed by tilting the surfaces of the mirrors with relation to each other.

According to the state of movement of the diaphragms the limits of the light displace themselves on the slit and effect on a film f , 80 moving rapidly behind the slit, transverse blackenings of different lengths.

In order to increase the sensitiveness of the arrangement it is further of advantage to prolong the path of the rays of light from 85 the reflecting diaphragms to the slit through which the image is to be projected. In order, however, to avoid making the apparatus too long, the course of the rays may be bent repeatedly by means of total reflecting 90 prisms (p in Fig. 4) or by means of simple mirrors.

In contradistinction from the form of construction described the arrangement may also be made in such a manner that the light 95 pencil is reflected successively by a plurality of small reflecting diaphragms, of different individual frequencies whereby merely an area of blackenings is produced on the film which shows the variations of the lower frequencies and over it superposed in correct 100 phase the high frequencies. This form is described more fully hereinafter, in connection with Fig. 6.

With such devices for recording sound 105 waves by optical means with the aid of a pencil of light influenced by the sound energy, comparatively small angular deflections of the oscillating mirror may be advisable. In order however to obtain thus 110 sufficient amplitudes of the light pencil at the recording point, there have heretofore been used correspondingly long light pointers such as are used in similar mirror recorders (mirror galvanometer etc.). For 115 acoustical recording apparatus such arrangements possess the disadvantage that they require great space particularly in the longitudinal direction. Consequently 120 the long frame which carries the apparatus can be easily set in vibration by external disturbances (shocks, trembling, etc.) and furthermore, the sound energy which exists in the space can cause the frame to set up vibrations of its own. According to this invention these disadvantages are avoided by the fact that the long light pointer which is 125 advantageous for the production of great amplitudes is bent by rigidly arranged total reflecting prisms or mirrors so that a com-

pact arrangement free from individual and disturbing vibrations is obtained. The long light pointer is therefore enclosed in a narrow space of the smallest dimensions which 5 for example may be of approximately cubical shape.

An example of constructional form of this 10 form or feature of the invention is diagrammatically shown in the Fig. 5. The sound waves, collected by the funnel shaped piece tr , strike on the reflecting diaphragm s_0 . The pencil of rays emitted from a source of light l and concentrated by the optical system o on the small mirror s_0 , is caused by 15 the oscillations of s_0 to make a transverse movement which is indicated by the transverse arrow, continues in the direction indicated by the arrow and is reflected successively by the mirrors s^1, s^2, s^3, s^4 . The 20 amplitudes of the ray of light which are rather large owing to the long optical path are then received upon the light sensitive strip f . Instead of the mirrors, other optical means may also be used for bending the 25 path of the light rays, e. g. total reflection prisms and the like. By the arrangement of the mirrors s^1 to s^4 the number of which may naturally be smaller or greater, the dimensions of the apparatus may be so selected 30 that it acquires a compact form free from individual oscillations and little sensitive to shaking.

Sound recording or reproducing devices 35 with movable diaphragms have, generally speaking, two defects. Either the individual oscillation of the element, capable of oscillating, falls within the range of the acoustic frequencies which are to be recorded (as for example in the gramophone etc.) in which case this fact is manifested 40 by a distortion of the true values of intensity of the sound at all frequencies which coincide with the fundamental tone of the vibrating number or its overtones. Or the 45 individual frequency of the vibrating element is intentionally displaced beyond the range of the sound waves which are to be received in which case no distortion can be detected, but the amplitudes of the oscillating element are comparatively small. The 50 latter way has heretofore not been practically realized, but it would be advantageous, in order to fix sibilant sounds, fineness of consonants, etc. With such an arrangement, 55 however, the recording of the lower sound vibrations (vowel tones and diphthongs) would be insufficiently executed accordingly, in this invention. A different method is followed which nature has already indicated in 60 the human ear. Several elements are used which are capable of oscillation and which are constructed so as to form reflecting easily influenced diaphragms of the smallest possible mass, the requirements of the registration 65 of the highest frequency being com-

plied with by the selection of a correspondingly higher individual frequency of one or the small mirrors. The remaining reflecting diaphragms are successively so selected that they possess suitably different individual oscillations in order to react strongly to vowel tones etc. In any case however for a reason above mentioned the damping of the diaphragms must be such that the above mentioned desired effect is counteracted to a 70 sufficient extent. On these small mirrors, whose axes of rotation must be all parallel, there is reflected successively a pencil of rays, which issues from a suitable source of light and is concentrated by an optical system on the plane where the recording takes place. The oscillating movement of each of the small mirrors is transmitted to the pencil of light. The small mirrors themselves are all mounted next to one another at one location in the space in order to allow the sound vibrations to act on all the mirrors in one and the same phase.

Fig. 6 shows diagrammatically by way of example a practical construction of the apparatus. On the bottom u of the sound conductor t diaphragms s^1, s^2, s^3 are mounted which possess different individual natural rates of vibration and are all provided with reflecting surfaces, the diaphragms all being 90 attached at one side only. By means of a source of light and of an optical system o a pencil of parallel rays is thrown successively with the aid of reflectors r^1, r^2 on to the oscillating small mirrors. The suitably controlled ray then acts upon the plane e which represents a light sensitive film or, if the oscillations are to be also electrically intensified, which may be a selenium or photovoltaic cell. In the latter case the rays of light may impinge against the reflecting diaphragms simultaneously.

The damping of the diaphragms may be so arranged as to somewhat decrease the sharpness of the resonance peaks in the acoustic curve, as stated. This damping may be accomplished in various ways. It may be caused by the cushioning effect of the air behind each diaphragm, in the restricted spaces between the various diaphragms and the portions of their supports r which are overlapped by the diaphragms, in Fig. 2 for example, and this cushioning effect may be adjusted by suitable adjustments of the mounting of the diaphragms.

The devices for recording sound waves for optical acoustic phenomena which have heretofore been described could also be used for other technical purposes (wireless telephony and the like). This could be done in all such cases where sound waves have to be transformed into electric oscillations or where an acoustic phenomenon has to be utilized electrically. In such cases a cell which is sensitive to radiation (e. g. a photo-

electric alkaline metal cell or the like (is employed, as shown in Fig. 7, for example). From the oscillating mirrors of the acoustograph more or less light is thrown in the 5 rhythm of the acoustic waves upon the photocell and varies rhythmically its electrical resistance. This fact can be utilized in the manner hereinbefore described for controlling high frequency oscillations or in 10 any other convenient manner. The apparatus described might represent in connection with a high frequency circuit and with an antenna, a sender for wireless telephony.

We claim:

13. 1. In acoustic apparatus, the combination of a fixed member having an orifice, a small diaphragm, covering said orifice and attached to said member at one side only, and having a reflecting surface, said diaphragm 20 being adapted to be set in movement by sound waves impinging against the same, and means for directing a ray of light upon the reflecting surface of the diaphragm.

2. In acoustic apparatus, the combination 25 of a sound collecting device having an orifice, a diaphragm secured at one side only and substantially covering the orifice of said device, and having a reflecting surface on the side opposite to that against which the 30 sound waves impinge, means for projecting a ray of light on the reflecting surface of the diaphragm, and means upon which the reflected light falls.

3. In acoustic apparatus, the combination 35 of a supporting member, having adjacent openings therein, a plurality of diaphragms covering said openings, exposed to sound waves on one side and having reflecting surfaces on the other side, said diaphragms having different individual frequencies, a source of light, and means for directing a beam of light therefrom against the reflecting surfaces of each of said diaphragms in succession, and from the last of said diaphragms 40 to a desired point.

4. In acoustic apparatus, the combination of a supporting member, a plurality of small diaphragms secured at one side only, exposed to sound waves on one side thereof 50 and having reflecting surfaces on the other side, said diaphragms having different individual frequencies, and means for directing light against said reflecting surfaces to be reflected thereby.

5. Means for recording sound waves comprising a device for collecting the sound energy and condensing the same, and a small reflecting diaphragm possessing high individual frequency, said diaphragm being attached at one side only and exposed to the 60 action of condensed sound energy.

6. Means for recording sound waves, comprising a device for collecting the sound energy and condensing the same, and a plurality of thin and small reflecting dia-

phragms fixedly secured at one side only and exposed to the action of the condensed sound energy.

7. Means for recording sound waves, comprising a device for collecting the sound 70 energy and for condensing the same, and a plurality of small reflecting diaphragms, possessing different individual frequencies, said diaphragms being rigidly attached at one side only and arranged so as to be 75 damped and exposed to the action of the condensed sound energy, whereby to record the structure of the lower vowel vibrations and of their diphthong and also the consonantal sibilant sounds.

8. Means for recording sound waves comprising in combination with a device for collecting the sound energy and for condensing the same, a plurality of small reflecting diaphragms attached at one side 85 only exposed to the action of the condensed sound energy, and a source of light emitting a pencil of light to be reflected in succession by the several diaphragms so that the light pencil reflected from the diaphragms may 90 make a record on a light sensitive band.

9. Means for recording sound waves comprising in combination with a device for collecting the sound energy and for condensing the same, a plurality of small reflecting dia- 95 phragms possessing different individual frequencies and rigidly attached at one side only and so as to be damped and exposed to the action of the condensed sound energy. a source of light emitting a pencil of light 100 to be reflected in succession by the several diaphragms so that the light pencil reflected from the diaphragms records a range of blackening on a light sensitive band, and several fixed mirrors for bending the path 105 of the light pointer for the purpose of obtaining a more compact arrangement which is less sensitive to concussion and individual oscillations.

10. Means for recording sound waves comprising in combination with a device for collecting the sound energy and for condensing the same, a plurality of small reflecting dia- 110 phragms attached at one side only and exposed to the action of the condensed sound energy, a source of light emitting a pencil of light to be reflected in succession by the several diaphragms so that the light pencil reflected by the diaphragms records a range 115 of blackening on a light sensitive band, and several reflecting members for bending the path of the reflected light pencil for the purpose of obtaining a smaller spaced arrangement which is less sensitive to concussion and individual oscillations.

11. In acoustic apparatus, the combination of a supporting member, having adjacent openings therein, a plurality of diaphragms covering said openings, exposed to sound waves on one side and having reflecting sur- 120

faces on the other side, said diaphragms having different individual frequencies, all of said diaphragms being secured at one side only, and all having parallel axes of rotation, a source of light, and means for directing a beam of light therefrom against the reflecting surfaces of each of said dia-

phragms in succession, and from the last of said diaphragms to a desired point.

In testimony whereof we affix our signatures.

JOSEPH MASSOLLE.
